UNITED STATES PATENT OFFICE

DANIEL MAPES, OF MAMARONECK, NEW YORK, ASSIGNOR TO WALTER KIDDE & COMPANY, INC., OF NEW YORK, N. Y., A CORPORATION OF NEW YORK

RELEASE DEVICE

Application filed January 29, 1929. Serial No. 335,809.

This invention relates to devices for effecting the release of a fluid under pressure, such as carbon dioxide, for example, when conditions arise which render desirable the release of such fluid by manually controlled means or by automatic means, such as those brought into operation by the rise of temperature incident, for example, to the outbreak of fire which is to be extinguished by the released fluid. A device of this character and intended for the same general purpose is shown and described in Letters Patent of the United States, No. 1,751,705, dated March 25, 1930, and in the construction now to be described, as in 15 that described in said patent, the container in which the fluid is held under pressure is sealed against leakage by a seal, such as a relatively frangible disc, which is normally held in place against a seat provided for it by a support which is held normally against movement by restraining devices which can be released so as to permit the support to yield and the seal to be ruptured by the pressure of the fluid against it, the support being 20 also formed so that the seal will give way to an abnormal internal pressure and permit the contents of the container to escape without rupturing the container. The present invention is concerned particularly with the 25 devices by which the support for the rupturable disc is normally held against movement, the object of the present invention being to secure greater compactness, greater adaptability to release either manually or automatically, easier adjustment, better protection 30 against accidental release, and greater sensitiveness in operation, requiring less force to retain the parts in closed position and to prevent the release of the fluid. The 35 invention will be explained more fully hereinafter with reference to the accompanying drawing in which it is illustrated and in which:

Figure 1 is a view in sectional elevation of 40 a structure which embodies the invention in approved form.

Figure 2 is a view of the same in elevation as seen from the right hand in Figure 1, a portion of the protection cap being also 45 shown.

Figure 3 is a detail view in section on the plane indicated by the line 3—3 of Figure 4.

Figure 4 is a detail view in horizontal section on the plane indicated by the broken line 4—4 of Figure 2.

As far as possible the same reference characters as those employed in said Patent No. 1,751,705 will be used herein to indicate like parts.

In the embodiment of the invention illustrated a base or body *a*, suitably chambered, is formed at *a*¹ for connection to a container *k*. At *a*² it is formed with a seat to receive a rupturable sealing disc *b* and is threaded internally to receive a bushing *c* by which the seal is pressed tightly against the seat *a*². The base or body is also threaded externally to receive a housing *d* which supports the devices to be described and has a connection, as at *d*¹, for the conduit through which the released fluid is to be conducted to the place of use. This outlet is closed during transportation of the equipment, by a plug *d*² provided with a small outlet *d*³ through which, in the event of development 50 of abnormal pressure, the fluid may escape, the plug being sealed against improper manipulation by a sealing wire *d*⁴. The seal *b* is supported against the internal pressure of the contents of the container by a support *e* which may take the form of a plunger with a free working fit within the bushing *c*. As shown the bore of the bushing is larger than the opening *a*³ between the container and the chamber of the bushing and the support *e* 55 supports the seal *b* externally over an area such that the seal will not give way to the normal internal pressure in the container. The support has a bore *e*¹ considerably smaller than the outlet *a*³ and communicating, as at *e*², with the chamber of the housing *d* and the discharge outlets *d*¹, *d*³. The area of the seal thus left unsupported is relatively small so that the seal will not give way under normal internal pressure but will give away if the 60 internal pressure rises above a predetermined degree. When, however, the support *e* is released and is free to move the seal will be ruptured by the internal pressure and the contents of the container will be permitted 65

thereby to escape in volume. All of the parts thus far described are arranged and operate substantially as described in the said Patent No. 1,751,705.

5 The support *e* is normally restrained from movement by two toggles *f*, *f*¹, the toggle *f* bearing against the end of a stem *e*³ of the support *e*, the toggle *f*¹ bearing against an adjusting screw *f*⁴, and the two toggles bearing against each other at their heels, as at *f*⁵, in a point which is at one side of the line between the upper and lower bearing points of the two toggles, pressure against the lower point of the toggle *f* tending to cause the toggles to swing further from such line. To prevent such movement of the toggles until the contents of the container are to be released, pressure is applied to one of the toggles, such as the lower toggle, and it is with the means for so restraining the toggles from movement under normal conditions but permitting the movement to take place when the contents of the container are to be released that the present invention is particularly concerned and will now be described.

20 A lever, preferably bent as shown and preferably consisting of two parts *g*, *g*¹, pivotally connected, as at *g*², is pivoted to the housing *d*, as at *g*³, and is arranged to bear normally against the toggle *f*, preferably through an adjusting screw *g*⁴. Obviously the lever *g*, *g*¹ operates practically as a single lever, but may be made in two parts, pivotally connected to each other, as shown, to avoid danger of binding and also for convenience in manufacture and assembling. The lever or the part *g* thereof is bent in substantially U-shape and is rotatably mounted at one end on a vertical axis and the point of bearing of the adjusting screw *g*⁴ is offset, opposite the bend of the lever, from a line through the axis of the lever and the pivotal connection of the two parts of the lever. When the lever is made in two parts, as shown, the part 45 *g*¹ may be supported on a projection *d*⁵ on a pillar *d*⁶ of the housing *d*.

It will be noted that the toggle *f* is provided with screw threads *g*⁵ for engagement with co-operating threads on the adjusting 50 screw *g*⁴, which bears at one end, as at *g*⁶, against the part *g*¹ of the two-part lever *g*, *g*¹, and at the other end is slotted, as at *g*⁷, for manipulation with a screw-driver or similar tool.

55 A detent or link *h*, adapted to separate under the influence of relatively high temperature, either by fusing or by burning, but preferably a flammable link of celluloid, having combined therewith an electrical resistance wire by which the link is ignited when the circuit of the resistance wire is closed, is engaged through one of its eyelets with a stud *d*⁸ carried by the pillar *d*⁶ of the housing, and through the other of its eyelets with a screw *g*⁸ carried by the lever *g*, *g*¹. So long

as the link *h* is intact and in engagement as described, it holds the lever *g*, *g*¹ in position to prevent movement of the toggles, but when the link separates, as by fusing or burning, or is disengaged by being slipped from the stud *d*⁸, the lever *g*, *g*¹ is released and permits the toggles *f*, *f*¹ to move thereby releasing the support *e* and permitting the contents of the container to rupture the seal *b* and to be discharged in volume.

70 It will be observed that the adjustable bearing screw *g*⁴ and the adjustable bearing screw *f*⁴ permit nice adjustment to be secured and that the parts are so formed, related and proportioned as to prevent release with the exercise of slight restraining force, so that the link *h* can be of light construction and therefore easily destroyed by heat and easily released by manually operated means, while at the same time all parts are securely held 75 against accidental release. It will be observed also that the construction permits of the isolation of the electrical connections at the posts *h*¹, *h*² on an insulating base *h*³ secured to the top of the housing.

80 For the manual release of the link *h* there is provided a lever *i*, pivoted at *i*¹, and having at *i*² a hook to engage the link and at *i*³ a surface to bear against the link and push it from the stud *d*⁸ when the lever is swung on its pivot as by a pull on a cable *i*⁴. The lower end of the lever is further formed, as at *i*⁵, for engagement with a spring *i*⁶ which serves to prevent accidental movement of the lever.

85 It will be understood that the invention is not limited in its application to the release of a fire extinguishing medium and that various changes in details of construction and arrangement can be made to suit different conditions of use and that the invention, except 90 as pointed out in the accompanying claims, is not restricted to the particular construction shown and described herein.

95 I claim as my invention:

1. In a device of the character described 100 and adapted for application to a container for fluid under pressure, a movable means acting normally to prevent the release of fluid from the container, a toggle lever normally cooperating with said means to prevent movement thereof, a lever having two parts pivotally connected and arranged to bear against the toggle lever to prevent movement thereof, a support for one of the parts of the second named lever, and a detent normally engaging 105 said part of said second named lever to prevent movement of the lever.

110 2. In a device of the character described and adapted for application to a container for fluid under pressure, a movable means acting normally to prevent the release of fluid from the container, a toggle lever normally 115 cooperating with said means to prevent movement thereof, a lever arranged to bear against the toggle lever to prevent movement 120

thereof, a detent normally engaging the second named lever, a stud engaging said detent, and means to disengage the detent from the stud and thereby release the second named lever.

second part of said second named lever to prevent movement of the lever.

This specification signed this 4th day of January, A. D. 1929.

DANIEL MAPES.

70

5 3. In a device of the character described and adapted for application to a container for fluid under pressure, a movable means acting normally to prevent the release of fluid from the container, a toggle lever normally cooperating with said means to prevent movement thereof, a lever arranged to bear against the toggle lever to prevent movement thereof, a detent normally engaging the second named lever, a stud engaging said detent, and a lever in operative relation with the detent to push the same from the stud and thereby release the second named lever.

75

10 4. In a device of the character described and adapted for application to a container for fluid under pressure, a movable means acting normally to prevent the release of fluid from the container, a toggle lever normally cooperating with said means to prevent movement thereof, a lever arranged to bear against the toggle lever to prevent movement thereof, a detent normally engaging the second named lever, a stud engaging said detent, a lever in operative relation with the detent to push the same from the stud and thereby release the second named lever and a device normally engaging the detent to prevent accidental disengagement of the detent from the stud.

80

15 5. In a device of the character described and adapted for application to a container for fluid under pressure, a movable means acting normally to prevent the release of fluid from the container, a toggle lever normally cooperating with said means to prevent movement thereof, a substantially U-shaped lever rotatably mounted at one end and arranged to bear opposite such end against the toggle lever to prevent movement thereof, and a detent normally engaging the second named lever to prevent movement thereof.

90

20 6. In a device of the character described and adapted for application to a container for fluid under pressure, a movable means acting normally to prevent the release of fluid from the container, a toggle lever normally cooperating with said means to prevent movement thereof, a lever having two parts pivotally connected and arranged to bear against the toggle lever to prevent movement thereof, one of said parts being substantially U-shaped and rotatably mounted at one end, the lever having a bearing against the toggle lever opposite its mounting at a point offset from a line through the point of mounting of the lever and the pivotal connection of the two parts of the lever, a support for the second part of the second named lever, and a detent normally engaging said
